PROCESS FOR THE MANUFACTURE OF
ALKALINE DICHROMATES

Jules Emile Demant, Cuise-Lamotte, France, assignor to Bozel-Maletra Societe Industrielle de Produits Chimiques, Paris, France, a corporation of France

No Drawing. Application February 3, 1932.
Serial No. 590,641, and in France March 21, 1931

21 Claims. (Cl. 23—56)

This invention relates to the manufacture of alkaline dichromates.

It is known that hitherto the manufacture of dichromates took place in two phases, first chromium oxide or bodies containing chromium oxide were treated in a furnace at temperature higher than 800° C. with alkalies with the object of the formation of mono-chromate, then the mono-chromate was decomposed by means of an acid in order to obtain the dichromate.

In accordance with the process of the present invention the dichromate is obtained in a single phase by causing chromium oxide, its derivatives or bodies containing the same, or metallic chromium, its alloy or mixtures comprising chromium, to undergo an oxidizing disaggregation by a dry method above 300° C. in the presence of bases or of mono-chromate in the quantity necessary for the reaction. The quantity of the alkali used in the process is at most 2 molecules of NaOH (or a corresponding alkali) for 1 molecule of Cr₂O₃, no addition of acid being necessary. Obviously, the reacting of one of the two reagents in the presence of the other cover the case of intimately mixing the two reactants.

As oxidizing agent, oxygen or gases containing the same, for example air, under pressure are used.

The pressure to be observed is a function of the temperature at which the operation is carried out. It is in fact known that dichromate decomposes above 380° C. liberating oxygen. It is therefore necessary to have a pressure of oxygen sufficient to reverse the direction of the reaction. In practice the temperature employed is between 300° and 600° C. and the pressure is not higher than 20 Kg/cm². As shown by the examples given hereinafter, good results are obtained with a temperature of 400° to 500° C. and a pressure of approximately 5 Kg/cm².

Two great advantages of the process will be seen immediately, the obtaining of the dichromate in a single phase and the economy of a considerable quantity of alkali, which is transformed into a less valuable salt in the case of the decomposition of chromate by acid.

It is expedient in certain cases to avoid the fusion of the product of reaction and to this end an excess of chromium can be used to serve as diluent, this excess being ultimately returned to the process of manufacture. It is necessary that the mixture should be very intimate. These intimate mixtures can be obtained by all the customary methods and for example by a preliminary chemical reduction of a mixture of chromium ox-

ide or of an alloy of metallic chromium and mono-chromate. The alkali thus liberated is intimately distributed in the mass.

The following examples illustrate the invention the parts being by weight:

Example 1

190 parts of chromium oxide and 106 parts of sodium carbonate suitably mixed, are treated in a furnace at 300—400° C. in the current of oxygen or air under slight pressure.

At the end of several hours the yield of sodium dichromate exceeds 91%.

The excess of chromium oxide employed is returned to the process of manufacture.

Example 2

A mixture composed of 100—150 parts of commercial ferrochrome containing 62.5% of chromium, and 50 parts of caustic soda is treated for 5 hours at 400—500° C. in a current of oxygen under 5 kgs. pressure.

The product obtained is treated with water. The solution contains a mixture of sodium mono-chromate and dichromate, the amount of dichromate being from 60 to 61%.

Example 3

190 parts of chromium oxide and 162 parts of anhydrous sodium mono-chromate are treated for 5—6 hours at 490° C. with oxygen under 5 kgs. pressure; the whole is then allowed to cool in the current of gas under pressure.

The product obtained is treated with water. The solution contains dichromate and a small quantity of monochromate, the amount of dichromate being about 93.85%.

Example 4

160 parts of Na₂CrO₄ and 250 parts of ferrochrome containing 68.2% of chromium are heated to 400° C. in a current of hydrogen for 2 hours in order to obtain a very intimate mixture of the reaction products.

Then, the whole is oxidized for 6 hours at 490° C. in a current of oxygen under 5 kgs. pressure and is allowed to cool in a current of gas under pressure.

The product obtained is lixiviated with water. The mono-chromate used has been transformed into dichromate the amount thereof being about 97.4%.

I claim:

1. A process for the manufacture of an alkaline dichromate, which consists in subjecting a sub-

of a compound acting as a base in the proportion at most equal to the stoichiometric quantity required to form dichromate and ultimately returning said excess to the process.

- 5 19. A process for the manufacture of an alkaline dichromate, which consists in mixing an alkaline monochromate together with a substance containing chromium the amount of monochromate being in proportion at most equal to the stoichiometric quantity required to form dichromate, then reducing said mixture by chemical means to produce an intimate contact of the components thereof and subjecting the product obtained to an oxidizing disaggregation, by the dry method, at a temperature above 300° C. and under pressure.
- 10 20. A process for the manufacture of an alkaline dichromate, which consists in mixing an alkaline monochromate together with a chromium oxide the amount of monochromate being in proportion at most equal to the stoichiometric

quantity required to form dichromate, then reducing said mixture by chemical means to produce an intimate contact of the components thereof and subjecting the product obtained to an oxidizing disaggregation, by the dry method, at a temperature above 300° C. and under pressure.

- 15 21. A process for the manufacture of an alkaline dichromate, which consists in mixing an alkaline monochromate together with metallic chromium the amount of monochromate being in proportion at most equal to the stoichiometric quantity required to form dichromate, then reducing said mixture by chemical means to produce an intimate contact of the components thereof and subjecting the product obtained to an oxidizing disaggregation, by the dry method, at a temperature above 300° C. and under pressure.
